MAGNETIC GRID

Richard F. Post, Walnut Creek, Calif., assignor to the United States of America as represented by the United States Atomic Energy Commission

Filed Aug. 20, 1959, Ser. No. 835,158

5 Claims. (Cl. 313—167)

The present invention relates to an improved electronic grid adapted for use in the control of electrical discharges in vacuum or gaseous atmospheres and, more particularly, to an electronic grid employing magnetic forces for controlling the passage of charged particles.

This application is a continuation-in-part of my co-pending application Serial No. 682,265, filed September 5, 1957, now abandoned.

Conventional grids or control electrodes employed in such as vacuum or gas tubes and more generically in any discharge device operate to produce a desired electrostatic field thereabout for applying forces of desired magnitude and direction to charged particles in the field thereof. Such grid fields are produced by the application of a charge or potential to the grid structure whereby the grid is surrounded by a predetermined electrostatic field. This conventional type of electronic grid has found wide acceptance and is employed universally in the control of electric discharges through space; however, certain fundamental limitations in this type of grid control have precluded the use thereof under certain circumstances.

The aforementioned limitation of conventional electrostatic grid control is based upon the fundamental characteristic of polarity found in all electrostatic fields. It is this field polarity which provides the effectiveness thereof and yet also results in the limitation upon the applicability. Thus a negatively charged grid having a corresponding electrostatic field thereabout operates to apply a repelling force to electrons, in such as a discharge tube for example, and the magnitude of the charge determines the magnitude of the force so as to control the number of electrons passing therethrough. However, in the instance such as above where a gaseous atmosphere surrounds the grid, ionization of the gas by electrons produces positively charged ions that are thus oppositely affected by the grid field, so as to be attracted toward the grid. A certain number of such ions actually strike the grid to produce a grid drain while many others attracted thereto form a sheath of positive charges about the grid to effectively cancel the grid field so that it no longer controls discharge. This phenomenon is well known and it is accepted in gaseous discharge devices, such as thyratrons, ignitrons, and the like, that grids are only operable to prevent discharge but exert no control thereover after discharge initiation and consequent ion production. Further, conventional grids in gas tubes or the like are ineffectual to cut off the tube or cease tube conduction and it has been heretofore necessary to lower the plate potential to cut off discharge in such devices.

It is widely appreciated in the electronic arts that great advantage would lie in the provision of complete grid control of gaseous discharge devices and, in fact, the applicability of such devices has been limited by the lack of same. The present invention provides such a grid. Former problems of controlling and stopping gaseous discharges are obviated by the present invention,

2

and the applicability of the present invention is in no wise limited to more conventional devices such as herebefore enumerated, the present invention being particularly useful in a device of the type disclosed and claimed in my copending patent application Serial No. 816,351.

It is an object of the present invention to provide electric discharge control means producing a magnetic field of a configuration to control by the magnitude thereof the passage of charged particles therethrough.

10 It is another object of the present invention to provide an electronic grid producing a magnetic field of variable intensity for the control of charged particle passage therethrough.

15 It is a further object of the present invention to provide an electronic control member employing magnetic rather than conventional electrostatic fields for controlling electrical discharges.

20 It is yet another object of the present invention to provide an electronic control electrode for similarly controlling the passage of charged particles of either polarity.

25 It is still another object of the present invention to provide a control electrode for gaseous discharge devices which retains control during discharge.

30 Numerous other advantages and possible objects of the invention will become evident from the following description of a single preferred embodiment of the invention chosen for illustration and depicted in the accompanying drawing, wherein:

35 Figure 1 is a plan view of an electronic grid embodying the present invention;

Figure 2 is a schematic illustration of a portion of the invention in section including a representative magnetic field configuration depicted by dashed lines and charged particle paths indicated by dotted lines;

35 Figure 3 is a plan view of an alternative embodiment of the grid of the present invention; and

Figure 4 is a perspective view of an ignitron having the embodiment of the grid of Figure 3 mounted in operative position therein.

40 Considering now a simple embodiment of the invention and referring to Fig. 1 of the drawing, there is provided as a grid structure 11 a planar double spiral of electrically conducting wire 12 or the like and comprising an outer spiral 13 extending from an external terminal 14 inward substantially to the center of a circle formed by the outer spiral turn. A second spiral 16 of wire is formed in the same plane as the first and extending from the first spiral end at the center outwardly in equal spacing between turns of the first spiral to a second terminal 17 located outside the spirals. There will thus be seen to be formed a double spiral grid structure 11 wherein each turn of the second spiral is equally spaced from a pair of turns of the first spiral. The wire 12 moreover is preferably of low resistance in order that a wide range of current magnitudes from zero to a relatively high value may be readily passed therethrough.

45 Energization of the grid is accomplished by a power supply 18 having a pair of output terminals separately connected by leads 19 and 21 to the spiral terminals 14 and 17. This power supply will be seen to be connected across the ends of the double spiral so that the two serially connected spirals 13 and 16 form a closed path between the power supply terminals for current flow therethrough. Provision is made for controlling the amount of current flowing through the grid, as for example by means integral with the power supply and controlled by a knob 22 thereon or a rheostat 23 connected in circuit with the grid and power supply.

50 Considering now the operation of the present invention, attention is first invited to the fact that the grid itself comprises a pair of conductors disposed in spaced

parallel relation and having current flowing therethrough in opposition. The significance of this situation is best understood by reference to Fig. 2 wherein alternate conductors will be seen to carry current in the same directions. Thus in Fig. 2, wire 13 carries current in one direction, say out of the plane of the drawing, and alternate wire 16 carries current in the opposite direction, say into the plane of the drawing. Current passing through a wire establishes a magnetic field encircling the wire with the field direction being dependent upon the direction of current flow so that each wire is surrounded by a magnetic field, as illustrated by the dashed lines H in Fig. 2 and extending in the direction of the arrows thereon. It will be seen from Fig. 2 that as adjacent wire portions carry current in opposite directions, the magnetic fields between each wire are additive.

As regards the action of the magnetic fields established by the grid, consider a stream of charged particles 31 approaching the grid. As any moving charged particle enters a magnetic field, it is acted upon by a resultant force perpendicular to the direction of particle motion and perpendicular to the magnetic field so that here it is seen that a charged particle entering the grid field is deflected. The degree of particle deflection is dependent in part upon the magnitude of the magnetic field and with a sufficiently strong field the particle loses substantially all motion toward the grid and is in effect turned away from the grid. As the magnitude of the magnetic field about a current carrying conductor decreases with distance from the conductor and is determined by the amplitude of the current in the conductor, it thus follows that the field strength between grid conductors is a function of the current through these conductors. With a very low grid current, only a weak magnetic field exists between the grid conductors so that charged particles approaching the grid in any direction but substantially directly toward the conductors experience only a slight deflection so that they pass through the grid. Increasing the grid current reinforces the magnetic field about the conductors thereof so that a lesser space between conductors is available for particle passage without such deflection as would prevent passage of the particles through the grid. A still further increase in grid current additionally strengthens the grid field until the field is sufficiently strong even directly between the grid conductors so that substantially all approaching charged particles are materially deflected and do not pass through the grid, and the grid may be said to be at cut-off. Inasmuch as the grid wire 12 is of low resistance, the power supply 18 may be of a practicable size and yet have an upper limit of sufficient proportions to produce an upper grid current magnitude at least as great as that corresponding to cut-off. The grid current may hence be varied over a wide range of magnitudes by adjustment of knob 22 or rheostat 23 to correspondingly vary particle flow through the grid 11 from a maximum at zero grid current to zero at cut-off grid current.

Regarding further the grid action of the present invention, it is noted that the grid action on approaching charged particles is the same regardless of particle polarity. Thus the grid impartially controls the passage of charged particles regardless of the charge polarity thereof. Even though the direction of deflection of positively and negatively charged particles is opposite upon entering the grid field, yet the same result is obtained insofar as the grid action is concerned, for particles of either polarity are deflected not to pass through the grid.

It is to be noted that the particular configuration shown in Fig. 1 is only illustrative of the present invention and a multitude of different grid wire configurations are possible. In this respect, reference is made to Fig. 3 wherein a grid 31 is illustrated as comprising a single folded grid wire 32 having a zigzag configuration. This grid 31 has alternate portions or sections of the wire thereof extending in substantially opposite directions so that a

current flowing through the grid actually flows in opposite directions in space through adjacent grid sections. Grid energization is accomplished from a power supply 33 connected through a switch 34 across the grid. With the particular circuit shown herein, the grid would be effective only to gate a discharge in such as an ignitron or other tube. With the switch 34 closed a sufficient current flows through the grid to establish a relatively strong magnetic field thereabout preventing the passage of charged particles therethrough. With the switch 34 open no grid energization is provided so that the grid exerts no influence upon charged particles passing therethrough. With this circuitry a pulsed grid operation is contemplated wherein a discharge is periodically gated by the grid and the switch may, of course, comprise such as an electronic valve controlled, for example, by some desired electrical phenomena associated with discharge passing through the grid. Although alternative circuitry is shown in Fig. 3, the grid structures of Figs. 1 and 3 are equally operable with either illustrated circuit, as well as with other energizing and control circuits.

Considering now the manner in which the magnetic grid may be operatively employed in a gas filled tube, e.g., an ignitron, to effectually precisely cut off the tube or otherwise exert control over the discharge therein and referring to Fig. 4, there is provided therein an ignitron 36 having a sealed low pressure envelope 37 of insulating material with an inwardly stepped anode supporting portion 38 at its top and a re-entrant cathode pool forming portion 39 at its bottom end face. An anode 41 is suspended transversely in the upper regions of the envelope by means of an electrically conducting support rod 42 extending longitudinally through portion 38 and externally secured thereto to an electrically conducting cap 43 engaging same. In the annulus formed at the bottom of the envelope between re-entrant portion 39 and the outer wall of the envelope there is contained mercury, forming a cathode pool 44. An igniter 46 is immersed in the pool and suspended by a lead-in conductor 47 secured thereto and leading exteriorly of the envelope through the recessed face of re-entrant portion 39. A lead-in conductor 48 is immersed in the pool 44 and similarly led exteriorly of the envelope through portion 39. All of the foregoing structural arrangement is conventional in ignitrons and the ignitron 36 may be connected in a circuit in a conventional manner to switch large amounts of current by connection of the anode cap 43 to a more positive potential than the cathode lead-in conductor 48. A trigger pulse may then be applied to igniter lead-in conductor 47 to initiate conduction through the tube. Once conduction is established in the conventional ignitron, however, there is no provision for precisely gating off the tube, it being possible to only terminate conduction in an unprecise manner by lowering the anode potential. In addition, the amount of current flowing through the ignitron cannot be controlled other than by pre-selection of the constants of the circuit in which employed. These difficulties of a conventional ignitron are overcome by a magnetic grid 49 in accordance with the present invention, e.g., similar to the zigzag grid 31 previously described, disposed transversely of the ignitron envelope 37 axially intermediate cathode pool 44 and anode 41 in the path of the discharge established therebetween upon pulsing of the igniter 46. More specifically, the magnetic grid 49 may be secured in the above-noted position within the envelope by fusing to the interior walls thereof or any other suitable attachment method familiar to those skilled in the tube art. The ends of conductor 51 forming grid 49 are led exteriorly of the envelope as shown at 52, 53 respectively, to facilitate series connection of the grid in an energization circuit such as either of those depicted in Figs. 1 or 3 and hereinbefore described. With the circuit of Fig. 3 connected to grid 49, for example, subsequent to initiation of conduction through the ignitron, the tube may be

gated off magnetically with substantial precision by the flow of a current pulse through the grid. Alternatively, with the circuit of Fig. 1 employed with grid 49, the current flow through the ignitron may be varied as desired in response to variation of the flow of magnetic field generating current through the magnetic grid.

As previously stated, the grid action of the present invention is dependent upon the establishment of magnetic fields that in whole or in part deflect and ultimately repel approaching charged particles of either polarity. As seen from Fig. 3, it is not necessary that the fields be established by currents flowing exactly in parallel opposition in space for satisfactory field configurations are possible with somewhat unparallel current flow. With a greater grid wire displacement a larger current therethrough is, of course, required to produce a desired magnetic field strength half way between same and thus an increased current flow can be made to compensate for lack of parallelism in current paths, the term "substantially parallel" being herein employed to encompass those configurations such as illustrated in Fig. 3 wherein the establishment of suitable fields are yet possible without exactly parallel grid sections.

There has been described above a novel magnetic grid having a wide range of utility and a multitude of possible structural variations within the scope of the invention and thus it is not intended to limit the present invention by the foregoing description but instead reference is made to the following claims for a precise definition of the invention.

What I claim is:

1. A magnetic grid for controlling charged particle discharge comprising at least one low resistance grid wire having more than two sections spaced apart and extending in substantially opposite directions in the same plane with said grid wire adapted for electrical energization to pass current therethrough of sufficient magnitude that magnetic fields established about adjacent sections of said wire deflect charged particles from the grid.

2. A magnetic grid comprising a uniplanar double spiral of low resistance grid conductor with a first spiral turning inward to the center and a second spiral turning outward from connection to the first spiral at the center thereof and spaced equally between turns of said first spiral, and means forcing a controllable electric

5 current through said double spiral to establish magnetic fields thereabout that are additive between adjacent grid conductors to deflect charged particles approaching the grid.

3. A magnetic control grid for controlling the passage of charged particles comprising means defining a low resistance electrical current path with alternate spaced portions in opposite directions and in the same plane, and means forcing a controllable electric current through said path for establishing additive magnetic fields between adjacent portions thereof for deflecting approaching charged particles in proportion to the magnitude of current flow through the path, said means having an upper controllable current limit of at least the current corresponding to magnetic deflection of all charged particles from paths through the plane of the current path portions.

4. A magnetic control grid for controlling passage of charged particles comprising folded conducting means defining opposed low resistance electric current paths in spaced substantially parallel disposition in the same plane, power supply means connected to energize said conducting means, and control means for controllably pulsing the current flow through said conducting means and establishing a current pulse of sufficient magnitude therein to magnetically gate off the passage of particles through the plane of the conducting means.

5. In an ignitron having at least a cathode pool and anode disposed at opposite ends of a sealed low pressure envelope with an igniter immersed in the cathode pool and separate input leads extending from the cathode pool, anode, and igniter exteriorly of the envelope, the combination comprising a magnetic control grid disposed transversely of the envelope intermediate the cathode pool and anode and comprising folded conducting means defining opposed low resistance electric current paths in spaced substantially parallel disposition and in the same plane with each end of the conducting means leading exteriorly through said envelope for series connection to a current source.
